HEMOSTAT

Theodore G. Blomberg, 3715 W. 9th St.,
Winthrop Harbor, Ill. 60096

Filed Apr. 30, 1969, Ser. No. 16,959

Term of patent 14 years

Int. Cl. D24—03

U.S. Cl. D83—1

FIG.1

FIG.2

FIG.3

FIG.4

FIG.5

FIG.6

FIG.7

FIG.8

FIG.9

FIG.10

FIG.11

FIG.12

FIG.13

FIG.14

FIG.15

FIG.16

FIG. 1 is a front elevation of a hemostat showing my new design, the same being shown in closed position;

FIG. 2 is a side elevation of the hemostat illustrated in FIG. 1;

FIG. 3 is a front elevation of the hemostat illustrated in FIG. 1 showing my new design, the same being shown in open position;

FIG. 4 is a top plan view of the hemostat illustrated in FIG. 1;

FIG. 5 is a sectional view of the hemostat illustrated in FIG. 1, taken along the line 5-5 thereof;

FIG. 6 is a front elevation of a second modified left-hand embodiment of the hemostat, the same being shown in closed position;

FIG. 7 is a front elevation of a third modified embodiment of the hemostat, the same being illustrated in closed position;

FIG. 8 is a side elevation of the hemostat illustrated in FIG. 7;

FIG. 9 is a front elevation of the hemostat illustrated in FIG. 7, the same being shown in open position;

FIG. 10 is a top plan view of the hemostat illustrated in FIG. 7;

FIG. 11 is a sectional view of the hemostat illustrated in FIG. 7 taken along the line 11-11 of FIG. 7;

FIG. 12 is a front elevation of a fourth modified embodiment of the hemostat, the same being illustrated in closed position;

FIG. 13 is a side elevation of the hemostat illustrated in FIG. 12;

FIG. 14 is a front elevation of the hemostat illustrated in FIG. 12, the same being shown in opened position;

FIG. 15 is a top plan view of the hemostat illustrated in FIG. 12; and

FIG. 16 is a sectional view of the hemostat illustrated in FIG. 12, taken along line 16-16 of FIG. 12.

I claim:

The ornamental designs for a hemostat, as shown and described.
